UNITED STATES PATENT OFFICE.

CHARLES TANRON, OF SAN FRANCISCO, CALIFORNIA.

GAME APPARATUS.

SPECIFICATION forming part of Letters Patent No. 728,327, dated May 19, 1903.

Application filed July 31, 1902. Serial No. 117,837. (No model.)

To all whom it may concern:

Be it known that I, CHARLES TANRON, of the city and county of San Francisco, State of California, have invented certain new and useful Improvements in Game Apparatus, of which the following is a specification.

This invention is a multiple game device by the use of which every imaginable game can be represented and played and in which fraudulent manipulation is impossible. Although every known and possible game of chance or otherwise can be played with this invention, it is especially devised for domestic or parlor use and for playing innocent games of chance, and it is particularly adapted to playing historical, geographical, scientific, and other games of educational purport.

The accompanying drawings, in which like reference characters indicate like parts in the several figures, are integral herewith as a medium of illustration.

Figure 1 is a plan of the preferred form of my said invention, illustrating its essential features. Fig. 2 is a diametral section of the apparatus shown in Fig. 1 looking toward the top of the sheet. Fig. 3 is a plan of a type of electric motor that I prefer to employ with this form of the apparatus.

As may easily be inferred from the drawings my games are disposed around the inner walls or galleries and also on top thereof when expedient of an amphitheater-like circular inclosure and are played by marbles or balls centrifugally propelled toward the walls of the amphitheater until all are lodged into numbered pockets or sections of an internal moat by means of a prism-shaped centrifugating-bat situated at the center of the inclosure or arena. It is now clear that not only can games of pleasure, education, or chance be played with this invention, but every political, national, and international event, land and sea battles, gladiatorial combats, horse-racing, slugging altercations, and any simulation of contest, &c., may be represented upon its walls and mimicked and fought to the finish within the amphitheater.

By referring to the said drawings it will be seen that my invention consists of a central arena, floor, or platform A, surrounded or inclosed by an upwardly-extending circular flange, projection, or barrier B, upon or

against which certain games are represented; one or more vertically-disposed annular rims C, bearing representations of other games on their inner faces to afford a choice of several games for a desirable variety, and which rim or rims C constitute, with the said flange, projection, or barrier B, what is herein termed the "amphitheater;" a centrifugating bat or discharger D, disposed at the center of the arena for propelling marbles or balls E promiscuously throughout the arena and toward and against the base of the said amphitheater, which marbles or balls E perform the executing, indicating, and registering functions in each game; a moat or groove F, subdivided into a suitable number of sections or a series of pockets for the reception and holding of marbles or balls lodged therein, and means, such as a motor G, for revolving the aforesaid bat or discharger D.

The arena A inclines from the amphitheater radially toward the discharger D, forming a concave surface for the purpose of imparting a centripetal tendency to all balls E, that have not been lodged in pockets F to return to contact with the revolving discharger and be thereby again and again propelled up the incline toward the amphitheater until each and every ball has been lodged in a pocket, at which time and not till then the result of the game is fully known. The incline or pitch of this arena is just sufficient to cause the balls to gravitate toward and against the discharger—say one-half inch in a foot. I find, however, by actual experiment that a five-eighth-inch incline in a twenty-inch arena works admirably well; otherwise the arena is made perfectly even and smooth, so as to offer no impediment to the proper radiation of the balls to the circumferentially-disposed pockets F, unless, of course, in cases of certain military, naval, or hall, field, or lawn contests, where men, ships, ninepins, or other dummies, represented as participants in the assumed contest, pose as targets for the propelled marbles. The pockets or sections of the groove or moat F are part of the arena and are regularly disposed and radially positioned at or near its outer or peripheral limits.

The amphitheater, as before stated, comprises the circular barrier or wall B and one, two, or a series of rims or rings C, which may

be vertical or slanting terraces. Preferably on the inside of this amphitheater each game is or different games are disposed. Only one form of rim C is illustrated herein, and the 5 same simply consists of a metal band or hoop bent over at the top and bottom, as seen in Fig. 2, so as to be capable of receiving and holding cards or other game representations and presenting their faces toward the arena. 10 These rims are made to fit snugly within the inner face of the barrier B and are removable for convenience in interchanging them or exposing the barrier itself to view to vary the game or games. If desired, they may be 15 bent horizontally and circumferentially outward, so as to flange over and cover the top of the barrier B for the purpose of furnishing horizontal views of the games represented on their inner vertical faces. This horizontal 20 disposition of the games I have represented on the barrier B by various cross-lining on the top thereof, which, like the inner face of the barrier, is divided into radially-disposed sections. These sections may be sim- 25 ply the prismatic or other disposition of colors or variegations thereof, or they may be serially-arranged numbers, as suggested, near the circumference of the arena in Fig. 1, such coloring or numerals to represent for cheap 30 constructions the divers phases or conditions of the respective game or of groups of games. It is to be understood that there is to be no limit to the number of radial sections or subdivisions of the moat F, barrier B, and rim or 35 rims C and that no two rims need be similarly divided. I have shown thirty-six of these subdivisions in Fig. 1 as suggestive of sundry games that comprise about that number of parts or points or multiples or submultiples 40 thereof. Moreover, in any case as many blank subdivisions as desirable may be interposed, so as to make up the number of odd or unnecessary subdivisions in particular cases. The subdividing of the moat into sections or 45 pockets is conveniently effected by vertically-disposed plates or partitions H, abutting against the inner face of the rim C or barrier B and disposed toward the arena radially, as indicated in Figs. 1 and 2.

50 The annular spaces marked J, K, and L, respectively, are (as may be seen in section in Fig. 2) but unessential parts of the apparatus, of which J is the outer bank of the moat or pockets F and is otherwise a continuation 55 of the arena A, while K and L constitute a base or outer molding of the barrier B and simply affect the design of the barrier, which of course may be indefinitely varied.

I have shown a line of blocks or men M cir- 60 cularly disposed around the arena and near its outer circumference. These are suggestive of ninepins or of military, naval, or other contestant representatives of war, field, lawn, parlor, or other like games, and of course may 65 be illimitably varied in forms, numbers, and positions to better represent and accommodate each respective game. The apparatus,

as illustrated, includes twelve of these nine-pin-like blocks M, one of which, M', toward the right, in each Figs. 1 and 2, is represented 70 as if knocked down by a ball E', which ball is shown lodged into an adjacent pocket numbered "5" at that part of the arena. I have represented the men or blocks M as pivoted each to a removable pin N, which prevents 75 their rolling down the arena when prostrated and which pin is adapted to be inserted into any one of a number of small holes that I provide in the arena for the purpose or that may be subsequently bored therein for the convenience of properly disposing the said men M as desired, so as to best display the ensuing contest.

The marbles E are shown six in number, one of which, E', as before seen, is within a 85 pocket at the right hand of the arena, and the remaining five are grouped around the discharger D at the center of the arena. These marbles may be called "bullets," "cannon-balls," "base-balls," "foot-balls," "billiard-balls," "cricket-balls," "tennis-balls," "lacrosse-balls," "tallying-balls," &c., according to the nature of the game to be played or contest to be decided. If the game should be astronomical or astrological in nature or 90 be some horoscopic system of telling fortunes, then each ball, of course, could be named, mentally or otherwise, after some star or constellation or as each particular case may suggest in order to impart a realism to 95 the game. I place no limit on the number, size, or composition of the balls or marbles to be used; but for ordinary use glass alleys or ivory or celluloid balls of about that size answer the various purposes to perfection. Of 100 course the marbles should be perfectly round to do good work. The balls or marbles may be of any color; but I prefer to produce them in different colors, so that each color may conveniently be listed for certain games to 105 represent any desired name or personality, especially in such cases where the complete features of the game are not fully represented on the particular ring or terrace C or the barrier or wall B of the amphitheater. I intend 110 that a manual of games, rules, and instructions shall accompany each apparatus.

The discharger D, I prefer to make square in plan design, with sides straight or concave, although slightly convex also answer 115 quite well. In elevation or vertical aspect I prefer the discharger to be prismatic and not pyramidal. The perpendicular discharging faces may be straight or curved. However, for military, naval, and ball contests the form 120 of a regular prism-frustum does admirably well, since it tends to impart to the balls an aerial flight, and for ordinary games an inverted frustum also works well. I have shown, however, a square prism with rectangular faces, which for general purposes is my preferred form. The discharger D acts by 125 rapidly revolving either to the right or left, so that its faces or their corners shall strike

and propel up against the amphitheatre the marbles or balls that are placed against it or that gravitate to the center by their centripetal tendency, due to the above-explained 5 declination of the arena toward its center, at which point, as seen, the discharger is disposed and operates. The revolution or operation of the discharger D may be effected by any desired motive means, such as a 10 pedal, a hand-crank, a spring, a turbine, or an electric or other motor, and so on. I have illustrated a carbon or dry battery motor. The discharger may have any name to coincide with or incidental to the nature of the 15 game to be played, such as "bat," "gun," "cannon," "citadel," "battery," "crosse," "dispenser," "dealer," and soon. As shown, the discharger is mounted upon the upper end of a vertically-disposed arbor P, Fig. 2, 20 which arbor passes through the center of the base-board of the arena and is rigidly connected with the shaft of the motor G thereunder.

I claim nothing for the motor or means of 25 rotating the discharger D, since, as before mentioned, I employ any suitable actuating device consistent with the extent of each particular apparatus. The motor shown and herein marked G is one of the ordinary dry 30 or carbon battery type. I have represented it as inclosed within a case or box Q, that is screwed or bolted centrally against the under surface of the base-board of the arena or floor

A, and remote from this case Q I have shown supports R for propping up the apparatus, so 35 that the bottom of the case shall be free from the table or plane upon which the said apparatus is placed, as well as to provide the convenience of legs therefor. The motor that I prefer to employ is one of known form, 40 which can be put in motion by merely turning the discharger and stopped by simply touching the top of the discharger.

I claim—

1. A game apparatus comprising an arena 45 upwardly inclined from its center to its periphery, a wall or barrier therearound, an internal moat following the base of the said wall or barrier, means for subdividing said moat into suitable sections or pockets, and a 50 central ball-discharger in the arena; substantially as described.

2. A game apparatus comprising an arena provided with a series of pockets and objective devices arranged around the center thereof, and a ball-discharger at said center, said arena inclining from said center upwardly in 55 all directions.

In testimony whereof I have signed my name to this specification in the presence of 60 two subscribing witnesses.

CHARLES TANRON.
